UNITED STATES PATENT OFFICE.

CHARLES E. PELLEW AND DORRIS W. WHIPPLE, OF NEW YORK, N. Y., ASSIGNEES TO
COLUMBIA PROCESS COMPANY, A CORPORATION OF NEW YORK.

CHEMICAL PROCESS.

BEST AVAILABLE COPY

No. 884,756.

Specification of Letters Patent.

Patented April 14, 1908.

Application filed April 16, 1907. Serial No. 368,593.

To all whom it may concern:

Be it known that we, CHARLES E. PELLEW and DORRIS W. WHIPPLE, citizens of the United States, and residents of New York city, county, and State, have invented certain new and useful Improvements in Chemical Processes, of which the following is a full, clear, and exact description, such as will enable others skilled in the art to which it appertains to carry out the same.

This invention relates broadly to the art of effectuating chemical reactions, but, more specifically it concerns various improvements in that art whereby certain elements may be brought into chemical combination with a given compound, while in a fluid or dissolved state, through the instrumentality of certain catalytic agents. Since, however, certain advantages characteristic of this invention prominently appear when it is resorted to for the purpose of producing tetra-chlorid of tin, it will be conducive to clearness to disclose it in such relation.

One object of this invention is to formulate a commercially practical method especially adapted to be continuously carried out for the purpose of changing the composition of certain substances, while in a fused or dissolved state or in the form of an emulsion, by subjecting such substances to the action of a gaseous element and by promoting reaction with a peculiar catalytic agent.

Another object within the contemplation of this invention is to subject a metal or its salts to the action of one or more members of the halogen group, in such a manner and in the presence of such other elements or compounds as will cause a reaction to readily take place under the control of the operating chemist.

Another object is to devise a chlorination process peculiarly adapted for the continuous production of tetra-chlorid of tin or its compounds and in which a substance such as mercuric chlorid may be employed in a catalytic capacity to promote the combination of the chlorin with the tin.

This invention in general seeks to provide a process of the nature described which, from a commercial standpoint, will in practice possess a high degree of efficiency and which, chemically considered, will be of the greatest possible simplicity, being composed of but few steps, all adapted for being performed at a minimum of cost, and individually of such

nature as to be capable of being readily carried out by any person skilled in the art to accomplish the purposes intended.

Other objects and advantages will be in part obvious and in part pointed out herein after.

This invention accordingly consists in the several steps and the relation and order of one or more of such steps with relation to each of the others thereof which will be exemplified in the process hereinafter described and the scope of the application of which will be indicated in the following claims.

To facilitate a better understanding of the character and commercial importance of the hereinafter described embodiment of this invention, it may here be noted that tetra-chlorid of tin, although heretofore commercially available mainly in the form of a solution of uncertain purity and strength, is very extensively used, especially in the textile arts as a mordant. The commercial production of a pure crystalline stannic chlorid hydrate has, however, never been accomplished at a reasonable price, although such a product would be greatly preferred by artisans inasmuch as they would be thereby enabled to exercise a more positive and certain control over their various operations, with a concomitant saving of expense.

In carrying out our process, we may start either with metallic tin or with a salt thereof, depending upon which is the most readily available from a commercial standpoint. Thus, assuming we desired to convert metallic tin into stannic chlorid, we would proceed in the following manner, it being understood that the proportions specified are merely relative and are subject to variation in conformity with the many diverse conditions under which our process may be carried out. 100 grams of metallic tin will preferably be first obtained in a granular or other comminuted form. Assuming that we desire to obtain solid or crystalline tetra-chlorid of tin containing water of crystallization as represented by the formula $\text{SnCl}_4 \cdot 5\text{H}_2\text{O}$, this granular tin will be put in a suitable vessel containing about 200 cc. of water or a solution of SnCl_2 . A small quantity of the catalytic agent will also be added and for this purpose about 1 gram of either metallic mercury or an equivalent or mercuric chlorid may be used. Chlorin gas, evolved in a suitable generator, will be led through a non- 110

corrosive tube, as of glass, and passed into the water containing the tin and mercury. A series of reactions will at once take place causing a dissolution and ultimate conversion of the tin into stannic chlorid. The chlorin acts upon the metallic mercury and converts it into mercuric chlorid in accordance with this reaction: $Hg + Cl_2 = HgCl_2$ and the resultant mercuric chlorid then 10 successively acts on the tin, first converting it to stannous chlorid and then into stannic chlorid as follows:

15 These reactions will continue to take place so long as any of the metallic tin remains undissolved, and ultimately all the mercury will be held in solution as the mercuric chlorid and the tin as the stannic chlorid. The same end may be obtained by starting with a solution of stannous chlorid, which preferably should be super-saturated and may advantageously be prepared from tin salt which 20 is of the composition expressed by the formula $SnCl_2 \cdot 2H_2O$ by mixing 100 grams of the salt with about 25 cc. of water and stirring up into an emulsion or mush. To this mush will be added about 1 gram of mercuric chlorid and the chlorin gas will then be passed through this mixture, which will immediately become heated by the reactions, forming a solution around the chlorin conveying tube, until ultimately the whole will 30 be in solution after about 30 grams of the gas has been used. This solution, like that of the preceding embodiment of this invention, contains the tin as a stannic chlorid and the mercury as a mercuric chlorid. 35 The reactions are substantially the same with the exception that here the action begins on stannous chlorid, while there the action begins on metallic tin which is initially converted to the stannous chlorid. It is 40 also to be understood that this invention may be carried out by melting the basis of the reaction. Thus we may fuse the stannous chlorid which occurs in the trade in the form of colorless transparent deliquescent 45 crystals (commonly called "tin crystals"). If we desire to obtain the stannic chlorid in the form of crystals containing considerable water of crystallization, we prefer to add a small amount of water to the fused tin crystals to enable the following reaction to ensue:

This reaction also takes place in the solutions mentioned in the two preceding adaptations 60 of this invention.

The separation of the stannic chlorid from the mother liquor containing the mercuric chlorid can be very easily accomplished by allowing the solution to cool until the stannic chlorid crystallizes out. These crystals

contain considerable water of crystallization as represented by the formula $SnCl_4 \cdot 5H_2O$. If desired a small amount of stannous chlorid may be added to precipitate the mercury. The crystals of stannic chlorid may be freed 70 from the mother liquor in a centrifugal machine or other straining means.

While various substances might be employed as a catalytic agent in certain adaptations of this invention, we have found that 75 mercury and the salts thereof are peculiarly adapted in practice for the production of tetra-chlorid of tin owing to the readiness with which the several reactions take place. It will thus be perceived that, as a result of 80 our exhaustive experiments and extensive investigations, we have discovered a peculiar treatment, with which as a basis we have been able to devise an inexpensive, simple and commercially satisfactory method of 85 continuously manufacturing tetra-chlorid of tin, either in the form of crystals of great purity, or as a solution of any desired strength. By this method, we may treat various residues of tin for the purpose of converting the 90 latter into the tetra-chlorid and this method can accordingly be utilized with great economy by the textile industries.

As our process could be carried out with 95 various ingredients and steps without departing from the spirit or scope of our invention, we intend that all matter contained in the above description shall be interpreted in an illustrative rather than in a limiting sense. We also desire it to be understood that the 100 language used in the following claims is intended to cover all the generic and specific features of the herein disclosed invention, and all statements of the scope thereof which, as a matter of language, might be said to fall 105 therebetween.

Having thus disclosed our invention, what we claim and desire to secure by Letters Patent of the United States is:

1. The art of promoting a chemical reaction consisting in treating a metal or salt thereof with a reactive substance in the presence of a mercurial catalytic agent.

2. The art of promoting a chemical reaction consisting in treating a metal or salt 115 thereof with an acid-forming element or compound thereof in the presence of a mercurial catalytic agent.

3. The art of promoting a chemical reaction consisting in treating a metal or salt 120 thereof with a halogen or compound thereof in the presence of a mercurial catalytic agent.

4. The art of promoting a chemical reaction consisting in treating a metal or salt 125 thereof with chlorin or a compound thereof in the presence of a mercurial catalytic agent.

5. The art of promoting a chemical reaction consisting in treating a metal or salt 130

thereof with chlorin gas in the presence of a mercurial catalytic agent.

6. The art of promoting a chemical reaction consisting in treating a quadrivalent metal or salt thereof with a reactive substance in the presence of a catalytic agent.

7. The art of promoting a chemical reaction consisting in treating a quadrivalent metal or salt thereof with an acid-forming element or compound thereof in the presence of a catalytic agent.

8. The art of promoting a chemical reaction consisting in treating a quadrivalent metal or salt thereof with a halogen or compound thereof in the presence of a catalytic agent.

9. The art of promoting a chemical reaction consisting in treating a quadrivalent metal or salt thereof with chlorin or a compound thereof in the presence of a catalytic agent.

10. The art of promoting a chemical reaction consisting in treating a quadrivalent metal or salt thereof with chlorin gas in the presence of a catalytic agent.

11. The art of promoting a chemical reaction consisting in treating tin or a salt thereof with a reactive substance in the presence of a catalytic agent.

12. The art of promoting a chemical reaction consisting in treating tin or a salt thereof with an acid-forming element in the presence of a catalytic agent.

13. The art of promoting a chemical reaction consisting in treating tin or a salt thereof with a halogen or compound thereof in the presence of a catalytic agent.

14. The art of producing stannic chlorid consisting in treating tin or a salt thereof with chlorin or a compound thereof in the presence of a catalytic agent.

15. The art of producing stannic chlorid consisting in treating tin or a salt thereof with chlorin gas in the presence of a catalytic agent.

16. The art of producing stannic chlorid consisting in treating metallic tin with a reactive substance in the presence of a catalytic agent.

17. The art of promoting a chemical reaction consisting in treating metallic tin with a halogen or compound thereof in the presence of a catalytic agent.

18. The art of producing stannic chlorid consisting in treating metallic tin with chlorin or a compound thereof in the presence of a catalytic agent.

19. The art of producing stannic chlorid consisting in treating a dissolved tin salt with chlorin or a compound thereof in the presence of a catalytic agent.

20. The art of promoting a chemical reaction consisting in treating a melted metal or salt thereof with a reactive substance in the presence of a catalytic agent.

21. The art of promoting a chemical reaction consisting in treating a melted metal or salt thereof with an acid-forming element in the presence of a catalytic agent.

22. The art of promoting a chemical reaction consisting in treating a melted metal or salt thereof with a halogen or compound thereof in the presence of a catalytic agent.

23. The art of promoting a chemical reaction consisting in treating metallic tin with a reactive substance in the presence of a fluid and a catalytic agent.

24. The art of promoting a chemical reaction consisting in treating metallic tin with a halogen or compound thereof in the presence of a fluid and a catalytic agent.

25. The art of producing stannic chlorid consisting in treating metallic tin with chlorin or a compound thereof in the presence of water and a catalytic agent.

26. The art of promoting a chemical reaction consisting in treating a solution of a metallic salt with a reactive substance in the presence of a catalytic agent.

27. The art of promoting a chemical reaction consisting in treating a solution of a metallic salt with a halogen or compound thereof in the presence of a catalytic agent.

28. The art of promoting a chemical reaction consisting in treating a solution of a metallic salt with chlorin or compounds thereof in the presence of a catalytic agent.

29. The art of promoting a chemical reaction consisting in treating a solution of a tin salt with a reactive substance in the presence of a catalytic agent.

30. The art of promoting a chemical reaction consisting in treating a solution of a tin salt with a halogen or compound thereof in the presence of a catalytic agent.

31. The art of producing a stannic chlorid consisting in treating a solution of a tin salt with chlorin or a compound thereof in the presence of a catalytic agent.

32. The art of promoting a chemical reaction consisting in treating a solution of stannous chlorid with a reactive substance in the presence of a catalytic agent.

33. The art of promoting a chemical reaction consisting in treating a solution of stannous chlorid with a halogen or compound thereof in the presence of a catalytic agent.

34. The art of producing stannic chlorid consisting in treating a solution of stannous chlorid with chlorin or a compound thereof in the presence of a catalytic agent.

35. The art of producing stannic chlorid consisting in treating metallic tin with chlorin gas in the presence of water and a catalytic agent.

36. The art of producing stannic chlorid consisting in treating fused hydrated stannous chlorid with chlorin gas in the presence of a catalytic agent.

37. The art of producing stannic chlorid

125

130

consisting in treating a strong solution of stannous chlorid with chlorin gas in the presence of a catalytic agent.

38. The art of producing solid $\text{SnCl}_4 \cdot 5\text{H}_2\text{O}$ consisting in treating metallic tin with chlorin gas in the presence of water and a catalytic agent until a solution of stannic chlorid is obtained, and then crystallizing out the stannic chlorid.

10 39. The art of producing solid $\text{SnCl}_4 \cdot 5\text{H}_2\text{O}$ consisting in treating fused hydrated stannous chlorid with chlorin gas in the presence of a catalytic agent, and then crystallizing out the stannic chlorid.

15 40. The art of producing solid $\text{SnCl}_4 \cdot 5\text{H}_2\text{O}$ consisting in treating a strong solution of stannous chlorid with chlorin gas in the presence of a catalytic agent, and crystallizing out the formed stannic chlorid.

20 41. The art of producing solid $\text{SnCl}_4 \cdot 5\text{H}_2\text{O}$ consisting in treating metallic tin with chlorin gas in the presence of water and mercury

or a salt thereof, and then crystallizing out the formed stannic chlorid.

42. The art of producing solid $\text{SnCl}_4 \cdot 5\text{H}_2\text{O}$ 25 consisting in treating fused hydrated stannous chlorid with chlorin gas in the presence of mercury or a salt thereof, and then crystallizing out the formed stannic chlorid.

43. The art of producing solid $\text{SnCl}_4 \cdot 5\text{H}_2\text{O}$ 30 consisting in treating a strong solution of stannous chlorid with chlorin gas in the presence of mercury or a salt thereof, and then crystallizing out the formed stannic chlorid.

In testimony whereof, we affix our signatures, in the presence of the two subscribed witnesses.

CHARLES E. PELLEW.
DORRIS W. WHIPPLE.
